US0D1032364S

(12) **United States Design Patent** (10) Patent No.: **US D1,032,364 S**
(45) Date of Patent: ** Jun. 25, 2024

(54) **PACKAGING TRAY**

- (71) Applicant: **QUALTIA ALIMENTOS OPERACIONES, S. DE R.L. DE C.V.**, San Nicolás de los Garza (MX)
- (72) Inventors: **Bernardo Velázquez Navarro**, San Nicolás de los Garza (MX); **Ariel Esaul Gómez Martínez**, San Nicolás de los Garza (MX); **René Martínez Sierra**, San Nicolás de los Garza (MX)
- (73) Assignee: **QUALTIA ALIMENTOS OPERACIONES, S. DE R.L. DE C.V.**, San Nicolás de los Garza (MX)

(**) Term: **15 Years**

(21) Appl. No.: **29/837,203**

(22) Filed: **May 3, 2022**

(30) **Foreign Application Priority Data**

Nov. 4, 2021 (MX) MX/f/2021/003329

(51) LOC (14) Cl. **09-07**

(52) U.S. Cl.

USPC **D9/456**
